UNITED STATES PATENT OFFICE.

BESSIE E. CRAMER, OF GARNETT, KANSAS.

CAN WASHER AND STEAMER.

Application filed August 2, 1926. Serial No. 126,605.

This invention relates to can cleaners and steamers designed primarily for dairy use.

The primary object of the invention is to provide a cleaner, washer and steamer for 5 cans, that includes in a single supporting frame, a trough adapted to receive water or other liquid for washing the cans and a steamer for steaming the latter that is safe, cannot burn out and has no flues to clean. 10 A further object of the invention is to provide a washer and steaming device for cans that provides a continuous flow of steam so as to thoroughly cleanse the cans and put the same in a sanitary condition.

15 This invention also consists in certain other features of construction and in the combination and arrangement of the several parts, to be hereinafter fully described, illustrated in the accompanying drawings and 20 specifically pointed out in the appended claims.

In describing my invention in detail, reference will be had to the accompanying drawings wherein like characters denote like 25 or corresponding parts throughout the several views, and in which:

Figure 1 is a top plan view of the washer and steamer forming the subject matter of the present invention.

30 Figure 2 is a fragmentary side elevation thereof.

Figure 3 is an end elevation.

Figure 4 is a perspective view of the steam generator per se.

35 Figure 5 is a sectional view taken through the valve for controlling the water to the generator.

Figure 6 is a perspective view of the device in its entirety.

40 Referring to the drawings in detail the reference numeral 1 indicates a frame made up of pipe bars as shown, arranged and connected in rectangular formation, and said frame is provided with supporting legs 2 and braces 3 are arranged between the side bars of the frame and the legs, while braces 4 are disposed between the end bars and the legs, as best shown in Figures 2 and 3.

45 Supported between the side bars and one end bar is a trough 5 which is semi-circular formation in cross section and the major portion thereof is provided with an open top and is adapted to be used to wash cans before steaming the same. The trough is 50 provided with a drain opening 6. The remaining portion of the trough is divided

from the washing portion thereof by a partition 7 and provides a water supply tank 8 for a purpose which will be presently described. A top 9 is provided for the supply 60 tank and an opening 10 is formed in said top so as to introduce water in said tank 8.

Secured to the underside of the trough and tank respectively is a casing 11 which is tapered toward one end and has secured thereto in a steam generator 12 disposed in the form of a substantially U-shaped hollow core. A nipple extends from one end of said core and has fixed thereto a valve 13 which controls the communication between the tank and the 70 core. The opposite end of said core has extending therefrom a pipe 14 which leads upwardly and terminates above an opening 15 formed in a platform 16 which is adapted to receive the cans in inverted position so that the upper end of said pipe 14 will project 75 into the can as will be readily apparent. Extending at an inclination from the lower edges of the opening 15 is a funnel shaped drain 17 for conveying the condensed steam 80 which drops in a receptacle 18 arranged below the funnel for that purpose. Any suitable heating means may be employed for heating the drum and as shown in Figure 6, a gasoline torch 19 is provided. The valve 85 is regulated through the instrumentality of a stem 20 which has its upper end projecting through the platform 16 in convenient reach of the operator and has its said end bent at right angles to the remaining portion, to provide a handle 21.

As shown in Figure 5, the valve is of a type, so that it not only controls the supply of water to the core, but can be turned so as to drain the core in the event the latter 95 becomes flooded.

90 From the above description and disclosure of the drawings, it will be apparent that the combined washer and steamer will be extremely advantageous in washing and putting milk and cream cans in a sanitary condition and after the cans have been washed, they are transferred to the platform 16 in the manner as above described, so as to be thoroughly steamed. In practice, it is advisable to heat the core before admitting any 100 of the water thereto, and then the valve should be regulated to admit very small quantities of water at a time so that all the water within the core will be turned into 105 steam immediately upon coming into contact with the walls thereof.

It is thought from the foregoing description that the advantages and novel features of my invention will be readily apparent.

I desire it to be understood that I may 5 make changes in the construction and in the combination and arrangement of the several parts, provided that such changes fall within the scope of the appended claims.

What I claim is:

- 10 1. A combined can washer and steamer of the character described comprising a frame, a trough depending from said frame and being of substantially semi-circular formation in cross section, legs for said frame, 15 braces between said legs and frame, a partition in said trough and providing a water tank, a steam generator disposed below said trough and tank respectively, means for admitting water to one end of the generator 20 in predetermined quantities, steam conveying means extending and rising from the opposite end of said generator, a platform supported by said frame and having an opening

therein through which said last mentioned means projects and a cone shaped drain extending at a downward inclination from the lower edges of said opening for the purpose specified. 25

2. In a can cleaning device, the combination with a water tank and a platform having a steam pipe extending therethrough, of a steam generator comprising a tapered casing, a substantially U-shaped hollow core arranged in said casing and having one end in communication with the steam pipe, means of communication between said tank and the opposite end of said U-shaped hollow core for supplying water to the latter, a valve for controlling the communication, a stem for controlling said valve and passing through the platform, and a heating means for the core and adapted to be disposed below said casing. 30 35 40

In testimony whereof I affix my signature.

BESSIE E. CRAMER.
